UNITED STATES PATENT OFFICE.

GABRIEL A. BOBRICK AND ARTHUR L. BOBRICK, OF LOS ANGELES, CALIFORNIA.

LIQUID DISPENSER.

Original application filed February 17, 1916, Serial No. 78,814. Divided and this application filed November 27, 1920. Serial No. 426,680.

To all whom it may concern:

Be it known that we, GABRIEL A. BOBRICK and ARTHUR L. BOBRICK, citizens of the United States, residing at Los Angeles,

5 in the county of Los Angeles and State of California, have invented a new and useful Liquid Dispenser, of which the following is a specification.

This invention relates to apparatus for 10 dispensing measured or predetermined quantities of liquid, and particularly to means for measuring or predetermining the quantity to be dispensed, and dispensing or discharging the same, by means of the force 15 exerted by a piston or plunger.

This application is a division of our previous application, Serial No. 78,814, filed February 17th, 1916, Patent No. 1,364,347 Oct. 8, 1920.

20 The invention is particularly adapted for dispensing liquid soap in public lavatories such as the lavatories of sleeping cars, clubs, hotels and the like, where from a single or common reservoir a number of dispensing devices are to be supplied either by gravity 25 or pressure and where the tubes or channels connecting the reservoir with the dispensers are extended horizontally as well as vertically or bent in curves whereby the liquid 30 is required to flow from the reservoir to the dispensers not simply vertically but horizontally and, in many cases, down and up again or vice versa.

An object of the invention is to construct 35 a liquid dispenser which will prevent the entrance of air into the tubes supplying the liquid to the dispenser.

Other objects are to provide such a construction and interrelation of parts as to 40 positively measure or determine the quantity of liquid dispensed by each operation of a plunger or piston; to prevent a continuous flow of liquid when the dispenser is in operation; to prevent all leakage from the 45 discharge nozzles so that the liquid is discharged only in the predetermined quantity and at the predetermined time and there is no drip or waste of the liquid.

A further object is to provide such interrelation of parts as shall be extremely simple to make and install and which shall be 50 efficient in operation and cheap to maintain.

The invention consists in the construction 55 and in the interrelations and combinations of parts hereinafter described and more par-

ticularly pointed out in the claims and will be more readily understood by reference to the accompanying drawings, forming a part of this specification, and in which:

Figure 1 is a vertical sectional view of a 60 lavatory, of a sleeping car, having installed therein a reservoir and dispensers embodying our invention;

Fig. 2 is a longitudinal sectional view of a 65 dispensing device embodying our invention the same being shown in normal or closed position;

Fig. 3 is a similar view of the construction shown in Fig. 2, the parts being in operated 70 position.

In Fig. 1 of the drawings we have shown or indicated a liquid supply reservoir 1 having a main tube 2 leading therefrom which is in turn connected to two branch tubes 3, each in turn connected with a tube 4 in turn 75 communicating with the dispensing devices proper 5 which dispensing devices 5 are connected therewith by suitable means such, for instance, as the couplings 6. See Figs. 2 and 3. The reservoir 1 is preferably provided with an opening by which it may be readily filled. This opening is preferably closed by a cap 8. The cap 8 is preferably provided with a vent 9 and valves or cocks 10 may be interposed between the reservoir 80 85 and the dispensing devices to close communication between the reservoir and dispensing devices when desired.

The body 11, see Fig. 2, is provided with suitable means, such as a shoulder 12, threaded portion 13 and nut 14 for securing the body 11 to the top plate 15 of a wash basin. As shown the body 11 is inserted through an opening made in the plate, resting with the shoulder 12 on top of the plate 90 and secured thereto by the nut 14. A washer 17 may be interposed between the shoulder 12 and the top of the plate 15 and a washer 17' between the nut 14 and the bottom of the plate 15. One or both of said washers may 95 be of the well-known split or lock nut type which when tightened will hold the body 11 securely in its set position. The body 11 is provided with a plurality of connecting axially arranged bores 18, 18' and 19 of different diameters, adapted to accommodate the operating parts or mechanism of the 100 dispenser.

A hollow plunger or piston 20 is mounted 105 in the bore, the piston portion being of such 110

diameter as to make a close working fit in the bore 18 of the body 11. The upper portion of the piston 20 is slightly reduced in diameter, as shown, to form the hub 24, thereby leaving an annular space or chamber 25 between such hub and the wall of the bore 18. The portion of the bore 18 below the piston we term the receiving chamber 18 and the portion above the piston the discharge chamber 25. The end or upper edge of the hub 24 is adapted to abut against the wall 26 of the chamber 25 and act as a valve for normally closing communication between the space or chamber 25 and the bore 19 to avoid all possibility of leakage in case the working fit of the piston is not sufficiently close. 27 represents an upward extension of the piston 20 forming a stem or piston rod of smaller diameter than the main piston 20. This piston rod or stem 27 extends through the bore 19 to the outside of the body 11. The portion 28 of the piston rod or stem 27 which connects with the hub 24 of the piston 20 is recessed or made of smaller diameter than the upper end of the piston rod, so as to form an annular space or chamber 29 between the recessed portion 28 of the stem 27 and the wall of the bore 19.

As shown the piston 20 is hollow and a portion of its bore 21 is contracted to form toward the upper portion of the piston the channel 33 which also extends within the reduced or stem portion 27. The nozzle 32 is preferably formed separate from the body 11 and provided with a threaded end to screw into the threaded opening 30. The nozzle 32 is provided with a duct or passage 31 and through the opening 30 communicates with the small bore 19.

Preferably the piston stem or rod 27 is provided on its outer end with a suitable push button or handle 35 and a suitable stuffing box is formed about the stem on the outside of the body 11. This stuffing box, as shown, consists of a suitable packing 37 (of asbestos or other suitable material), a gland 38, and an internally threaded cap 39 engaging the external thread of the end of the body 11. This stuffing box is provided primarily to compensate for possible wear between the stem 27 and wall of the bore 19.

The lower or open end of the hollow piston 20 is preferably internally threaded to receive a similarly threaded hollow plug or bushing 40. The top of the bushing 40 forms a seat for a valve 22. The valve 22 is normally held on its seat by the spring 23. The tension of the spring 23 should be such as to hold the valve 22 seated against the normal pressure of liquid in the receiving chamber of the dispenser.

The delivery mechanism comprises the valve 22, preferably provided with a hub 41 and two rods 42, 43 which serve as guides for the valve. A washer 44 may be interposed between the valve 22 and its valve seat. A plug 45 is screwed into the bushing 40 and is so formed on its outside as to accommodate a packing or cup 46 made of leather or other suitable material. The plug 45 is provided with a channel 47 and with one or more perforations or ports 48 in its side wall and with a perforation 49 in its end wall. This perforation 49 serves as a guiding channel for the rod 43. The channel 33 serves as a guide for the rod 42. The valve 22 is thus held in axial position in relation to the chamber 21 and the valve seat 44 when opening or closing. The perforations or ports 48 serve as passages for the liquid from the receiving chamber 18 into the piston chamber 21 when the valve 22 is raised. Some liquid will, of course, also pass through the channel 49.

Provision is made for opening the discharge valve 22, in the piston 20, by positive action instead of by the compression of the liquid in the receiving chamber by the force of the piston on its inward stroke, as in the construction illustrated in Figs. 2 to 7 of our copending application for patent for Liquid Dispenser Serial No. 78,814 filed February 17, 1916. For this purpose the open end of the receiving chamber 18 is closed with a plug 50, provided with a channel 51, the inner end of which is closed to form an anvil or stop 52. The diameter of the inner end of the plug 50 is contracted to form a hub 53, and one or more perforations or ports 54 connect the channel 51 with the receiving chamber 18. When the valve 22 is seated the guiding rod 43 extends outside the plug 45 about half way between the top of the anvil 52 and the bottom of said plug 45.

A spring 61 is located in the lower portion of the bore 18, one end of the spring abuts against the inner end of the plug 50, the other end against the lower end of the plug 47. The spring forces the piston outwardly when pressure on the push-button 35 is released and it holds the valve 22 seated when the dispenser is at rest.

A port or ports 60 connect the piston chamber 21 with the chamber 25.

The operation is as follows: The person desiring a supply of liquid soap pushes the push button 35 inwardly thus forcing the piston inwardly until the end of the guiding rod 43 reaches the anvil 52; the further advance of the piston inwardly, with the rod 43 resting on the anvil, holds the valve 22 stationary and the further inward movement of the piston disengages the valve 22 from its seat thus establishing communication between the receiving chamber 18 below the piston and the piston chamber 21. The reservoir 1 being in direct communica-

tion with the receiving chamber 18 and the liquid in said receiving chamber being uninterruptedly under pressure it flows from said chamber into the piston chamber, when 5 the valve 22 is opened, thence into the space above the piston, vacated by the piston. When the pressure on the push button is released and the piston by the tension of the 10 spring is pushed outwardly the valve 22 remains open until the piston has reached a point at which the rod 43 will lift itself from the anvil. The liquid entrapped in the chamber above the piston will be forced out through the nozzle by the further outward 15 advance of the piston. To prevent a continuous flow of the liquid from the nozzle when the valve 22 is open, the distance of the extension of the guiding rod 43 outside the plug 45 and the length of the recess 20 29 in the piston rod are so gaged that the moment the guiding rod 43 reaches the anvil the end 55 of the recess closes the outlet 30, see Fig. 3. It is understood that about half of the motion of the piston on its inward stroke and about half of its motion 25 on the outward stroke are lost.

We claim:

1. The combination with a hollow body having an outlet near one end and an inlet 30 near the other end, a hollow piston mounted in said body to reciprocate therein between said inlet and outlet, a receiving chamber formed below said piston and a discharge chamber formed above said piston, 35 said piston provided with a bore having inlet and outlet ports; a valve seat and valve within said bore to open and close communication between the inlet and outlet ports; a stem extending from the valve through said 40 valve seat and adapted to contact with a portion of said body to open said valve upon each inward stroke of said piston, and a spring holding said valve seated until posi-

tively opened by contact of the valve stem with the body. 45

2. The combination with a hollow body having an outlet near one end and an inlet near the other end, of a hollow piston mounted in said body to reciprocate between said inlet and outlet, a receiving chamber being formed below said piston and a discharge chamber being formed above said piston, a spring adapted to exert its tension to move said piston to its upper position, a stem for said piston extending out through 50 said body, said piston provided with a port near its stem end, a valve seat formed within the piston, a valve within said piston co-operating with said seat and having a stem extending through said valve seat and adapted 55 to contact with a portion of said body to open said valve upon the inward stroke of said piston, and a spring normally holding said valve seated. 60

3. The combination with a hollow body 65 having an outlet near one end and an inlet near the other end, of a hollow piston mounted to reciprocate in said body between said inlet and outlet, a receiving chamber being formed below said piston and a discharge chamber being formed above said piston, a stem for said piston projecting through said body, said piston provided with a port near its stem end, a valve seat formed at the lower end of said piston, a valve within said piston having a stem extending through said valve seat and adapted to contact with a portion of said body to open 70 said valve upon the inward stroke of said piston, a spring normally holding said valve seated, and a spring mounted in said receiving chamber to exert its tension to move said piston to the upper limit of its stroke. 75 80
